(57) **CLAIM**

The ornamental design for a faucet as shown and described.

DESCRIPTION

FIG. 1 is a perspective view of the claimed design; FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The evenly-dashed broken lines show the boundary of the break lines and portions of the faucet that form no part of the claimed design. Break lines having a jagged element are not part of the claimed design and show unspecified lengths of the portions are possible: the appearance of any portions of the article between the break lines forms no part of the claimed design.
